BOTTLE HOLDER FOR MIXING MACHINES

James Kantor, Chicago, Ill., assignor to The Liquid Carbonic Corporation, Chicago, Ill., a corporation of Delaware

Application November 9, 1940, Serial No. 364,982

16 Claims. (Cl. 259—54)

The present invention relates to improvements in beverage mixing machines and particularly to improvements in the container supporting element thereof.

The present commercial type of beverage mixing machine usually comprises a structure provided with a plurality of supporting elements adapted to receive and clamp the filled containers. These elements are so mounted that they may be tilted and uprighted during their path of travel and, at the same time, the container supported, thereby rotated on its longitudinal axis either during the tilting or uprighting of the container or between the tilting and uprighting movements.

The supporting element usually comprises a structure including upper and lower clamping members. These clamping members have portions rotatably mounted thereon, which portions engage and container and one of these clamping members is provided with means for automatically centering the container as it is fed to the supporting member.

In certain of the commercial structures, this centering means is included in the supporting member for engaging the bottom of the container and generally comprises a cup-like structure adapted to receive the bottom of the container and a table or plate within the cup-like structure normally lying in the plane of the top of the cup-like structure. This table is yieldingly moved or held in this normal position so that as the container is fed thereto and when the container is clamped in position, the bottom of the container will move down into the cup-like structure, causing the container to be centered.

One of the objections to this particular type of supporting member is that it is not particularly adapted for receiving and holding comparatively large containers. For one reason, the yielding means for maintaining the table in its normal position, in the larger containers, must be made so heavy or strong that, from a practical standpoint, such an arrangement would be unsatisfactory.

It is one of the objects of the present invention to provide a mixing machine having an improved supporting member for the container which will handle the larger size container conveniently and which, at the same time, may also handle various sized containers with a minimum of adjustment or change of parts.

For the purpose of disclosing the invention, I have illustrated an embodiment thereof in the accompanying drawings, in which:

Fig. 1 is a longitudinal section of so much of a mixing machine as is necessary for illustration, embodying my invention;

Fig. 2 is a longitudinal sectional view of one of the container supporting structures;

Fig. 3 is a plan view thereof with the top clamping arm removed;

Fig. 4 is a longitudinal section of a modification of the bottom supporting arm of the container support;

Fig. 5 is a plan view thereof; and

Fig. 6 is a developed view of the cam for maintaining the centering means retracted.

Referring to the structure illustrated in Fig. 1, I provide a mixing machine which embodies a base 1 including sides 2 on which base the apparatus is assembled. On the top 3 of the base, I mount a locating platform 4 which is adapted to carry a plurality of supporting elements 5, each of which is adapted to receive and support a container.

Each of these supporting elements comprises, in general, a bracket including a bottom supporting arm 6 having a supporting platform 7 and a top clamping arm 8 having a rotatable top clamp 9.

There are a plurality of these container supports disposed around the rotatable supporting member 4 and each is mounted for oscillation on a journal or shaft 10 carrying a beveled gear 11 driven from a bevel pinion 12 and driving a bevel pinion 13 at the bottom end of a shaft 14, to be more fully hereinafter described. The pinion 12 is mounted on a suitable shaft, the opposite end of which carries a bevel pinion 15 in turn adapted to mesh with a driving gear 16 so that as the head 4 rotates, the containers carried on the supporting members will be rotated on their vertical axes. The container-supporting elements, due to the fact that they are journaled on the shafts 10, may tilt and upright so as to cause an oscillation of the container in a plane radial to the head 4 and this oscillation is imparted through the means of a suitable cam structure 17 on which a roller 18 of each of the supports is adapted to ride. This cam is so developed as to permit the supporting structures to oscillate about the shaft 10 as the head 4 is rotated throughout its orbit.

The gear 16 is driven by a vertically disposed sleeve 19 driven from a gear 20 in turn driven by a gear 21 on a shaft 22 carrying a bevel gear 23 driven from a bevel gear 24 in turn driven by an electric motor 25. By this arrangement, the mechanism for rotating the container on its lon-

gitudinal axis is driven by a different mechanism than that which rotates the head 4.

The support 4 is provided with a vertical sleeve 26 telescoping the sleeve 19, both of which surround a supporting shaft 27 and this sleeve 26 is provided with a gear 21 driven by a suitable gear and belt train from an electric motor 28 so that the head will be rotated, thereby causing the supports to move in a circular orbit during which the containers are tilted and uprighted and rotated on their longitudinal axes.

The containers are fed into the supports by suitable infeed stars 29 and after they have completed their orbit of travel, are removed from the supports by outfeed stars adjacent the infeed stars and having substantially the same construction.

Referring now more specifically to the supports 5 more particularly illustrated in Figs. 2 and 3, these supports comprise a bracket including a vertical hollow post 30 having reciprocably mounted therein a stem 31. The upper end of this stem carries a bracket or arm 8 of the supporting member, at the outer end of which is rotatably mounted a substantially cone-shaped or skirted container-engaging member 32. This stem 31 is biased in a retracted position by a relatively heavy spring 33 bearing at one end against a shoulder 34 on the sleeve 30 and at its lower end against a shoulder 35 on an extension 36 of the stem 31. This extension 36 at its bottom end carries a roller 37 adapted during the infeed and outfeed portion of the travel of the support to engage and bear upon a cam 38 stationarily mounted on the stationary head 39 of the framework of the machine. During the time that the roller 37 bears upon or engages the cam 38, the stem 31 will be moved upwardly to thereby raise the container-engaging member 32 to sufficient distance to permit a container to be inserted below the same and into the support.

The hollow sleeve 30 is also provided with a bottom or lower arm 40 in which is rotatably mounted, in axial alignment, with the engaging member 32, the shaft 14. This shaft is rotatably mounted in an enlarged housing 41 on the arm 40 which housing contains suitable ballbearings 42 for the shaft and on the upper end of the shaft, I mount a table or container support 43 which, it will be noted, is removably connected to the shaft by means of a locking screw 44. The arm 40 also carries the roller 18 which, in cooperation with the cam 17, is adapted to impart to the support 5 an oscillating movement.

Surrounding the shaft 14, at the upper end thereof, I provide a cup-like centering member 45 having inwardly tapering walls 46 and which is vertically movable on the shaft, although being locked to rotate therewith through the medium of a pin 47 extending through the hub 48 of the member and engaging in a longitudinal slot 49 in the shaft 18. By this arrangement, the centering member may be raised and lowered to the shaft but, at the same time, is mounted to rotate with the shaft.

This centering cup 45 is adapted to be engaged by a collar 50 surrounding the shaft 14 and axially movable thereon. This collar is mounted between the yoke arms 51 of a lever and on suitable pivot pins 52 extending through the yoke arms and into the collar. This lever, in turn, is pivoted on the sleeve 30 through the medium of pivot pins 53 which extend into bosses extending laterally from the sleeve and the yoke arms 51 at their rear carry a roller 54. This lever, in-

cluding the yoke arm 51, is biased in a direction to raise the collar 50 through the medium of a coiled spring 55 having one end bearing on the rear end of the lever formed by the yoke arms 51 and against an adjustable stop 55' threaded into a hollow boss 56 on the sleeve 30. By this arrangement, the table 43 is axially stationary, while the centering member 45 is axially movable and may be raised into centering position by the comparatively light spring 55 due to the leverage obtained through the lever including the yoke arms 51. It is obvious that with the container-engaging member 32 raised under the influence of the cam 38 and roller 37 during the infeed of a container, the container can be fed into a position with its top immediately beneath the engaging member 32 and with its bottom resting on the table 43. During this infeed movement, the roller 54 rides on a stationary cam 57 on the head 39 and the centering cup 45 is in its retracted position so that its top is in the same plane as or below the plane of the table 43 permitting a bottle to slide readily on to the table 43. As the rotating head or support 4 moves the container support in its orbit, this roller rides off of the cam 57, thereby permitting the spring 55 to come in action, raising the centering member 45 and, due to the inwardly inclined walls 46 thereof, which are somewhat cone-shaped, these walls will engage the bottom of the container, centering the same on the table 43 and assisting in maintaining the container in its clamped position. It should be noted also that, as the support moves from its infeed position, the roller 37 moves off of the cam 38, thereby permitting the engaging member 32 to move downwardly under the influence of the spring 33, thus clamping the container in position on the support.

Obviously, as the support moves to its outfeed position, the roller 37, again engaging the cam 38, will raise the engaging member 32 and the roller 54, engaging the cam 51, will retract the centering member 45, thus permitting the outfeed star to engage and remove the container from the support.

Due to the fact that the table or plate 43 is readily removable from the shaft 14 by disconnecting the screw 44, and due to the fact that the centering device 45 is also readily removable from the shaft 14 by the removal of the screw 47, the machine may be quickly changed to accommodate different sized containers, as all that is necessary to accommodate the different sized containers is to attach to the shaft 14 tables 43 and centering devices 45 of a size appropriate for the container to be used.

In Figs. 4 and 5, I have illustrated a modification of my device, wherein even the change of the tables 43 and the centering device 45 is rendered unnecessary to accommodate different sized containers. In this structure, the shaft 14', corresponding to shaft 14, is provided with an enlarged head 58 which corresponds to the table 43. This head or table 58 is provided with a plurality, in the structure illustrated four, of radial slots 59. Surrounding the shaft 14' is a collar 60 having an annular groove 61 within which operate the pins 52 of the fork arms 51, whereby the collar is rotatable relatively to the fork arms, with the shaft 14' but is vertically movable on the shaft 14' through the instrumentalities of the fork arms 51 and their pins 52. This collar has pivoted thereon four lever arms 62, one for each of the recesses 59, which lever arms are provided with fingers 63 located beneath the head

58 and outside of the inner wall of the slots 59. The outer ends of these lever arms are provided with fingers 64. Therefore, when the collar 60 is raised by raising the outer end of the fork including the arms 51—51, the fingers 63, engaging beneath the table 58, will cause the outer ends of the levers 62 and the fingers 64 to swing upwardly and inwardly until they embrace and come in contact with the sides of the container supported on the table 58, thus centering the container on the table and holding the bottom of the container gripped against lateral displacement. The lever including the arms 51—51 is of the same construction as that illustrated in Figs. 2 and 3. By this arrangement, it will be noted that any size bottle, just so it comes within the confines of the fingers 64, may be clamped in position upon the support and that the fingers will grasp and center the same, irrespective of the diameter thereof.

I claim as my invention:

1. In a beverage mixing machine, a container-supporting element comprising a bracket including upper and lower arms, one of which is movable relatively to the other to engage and clamp the container, a downwardly facing container engaging clamp carried by and rotatable with respect to said upper arm, an upwardly facing cup-like clamping member carried by and rotatable with respect to said lower arm, an axial stationary central table within said cup-like member, a pivoted lever supporting at one end said cup-like member, and yielding means biasing the opposite end of said lever to move said cup-like member toward said downwardly facing clamp.

2. In a beverage mixing machine, a container-supporting element comprising a bracket including upper and lower arms, one of which is movable relatively to the other to engage and clamp the container, a downwardly facing container engaging clamp carried by and rotatable with respect to said upper arm, an upwardly facing container centering member rotatable with respect to said lower arm, an axial stationary supporting member carried by and rotatable with respect to said lower arm associated with said centering member, a pivoted lever having an end connected to said centering member, and yielding means biasing the opposite end of said lever in a direction to move said member toward the downwardly facing clamp to cause the bottle to be embraced and centered by said centering member.

3. In a beverage mixing machine, a container-supporting element comprising a bracket including upper and lower arms, one of which is movable relatively to the other to engage and clamp the container, a downwardly facing container clamp carried by and rotatable with respect to said upper arm, an upwardly facing axially stationary container support carried by and rotatable with respect to said lower arm, an axially movable centering member associated with said support, a pivoted lever having one end connected to said centering member and yielding means biasing the opposite end of said lever in a direction to move said member toward the downwardly facing clamp, said members, when in container insertion position, lying in substantially the same plane.

4. In a beverage mixing machine, a container-supporting element comprising a bracket including upper and lower arms, one of which is movable relatively to the other to engage and clamp

the container, a downwardly facing container engaging clamp carried by and rotatable with respect to said upper arm, an upwardly facing axially movable container centering member having portions engaging the bottom of the container and axially centering the same carried by and rotatable with respect to said lower arm, an axially stationary supporting table member associated with said centering member, a pivoted lever having one end connected to said centering member, and yielding means biasing the opposite end in a direction to move said member toward the downwardly facing clamp.

5. In a beverage mixing machine, a container-supporting element comprising a bracket including upper and lower arms, one of which is movable relatively to the other to engage and clamp the container, a downwardly facing container engaging clamp carried by and rotatable with respect to said upper arm, an upwardly facing axially stationary container supporting table carried by and rotatable with respect to said lower arm, an axially stationary driving spindle extending downwardly from said table, driving means carried by said spindle, centering means longitudinally movable with respect to said table support and moving said container into center position on said table by said longitudinal movement and means drivingly connecting said spindle with said centering means.

6. In a beverage mixing machine, a container supporting element comprising a bracket including upper and lower arms, one of which is movable relatively to the other to engage and clamp the container, a downwardly facing container clamp carried by and rotatable with respect to said upper arm, an upwardly facing axially stationary container supporting table carried by and rotatable with respect to said lower arm, an axially stationary driving spindle extending downwardly from said table, driving means carried by said spindle, longitudinally movable centering means associated with said table having portions adapted to embrace the bottom of the container and maintain the same against lateral displacement, movable into and out of embracing position by the longitudinal movement thereof, and yielding means for biasing said centering means in embracing direction and means drivingly connecting said spindle with said centering means.

7. In a beverage mixing machine, a container-supporting element comprising a bracket including upper and lower arms, one of which is movable relatively to the other to engage and clamp the container, a downwardly facing container engaging clamp carried by and rotatable with respect to said upper arm, an upwardly facing axially stationary supporting table carried by and rotatable with respect to said lower arm, a centering clamp rotatable with said table and longitudinally movable relatively thereto, a lever having one end operatively connected with said centering clamp, and yieldable means biasing the opposite end of said lever in a direction to move said centering means into centering and clamping position.

8. In a beverage mixing machine, a container-supporting element comprising a bracket including upper and lower arms, one of which is movable relatively to the other to engage and clamp the container, a downwardly facing container engaging clamp carried by and rotatable with respect to said upper arm, an upwardly facing axially stationary supporting table carried by and rotatable with respect to said lower arm,

an axially stationary driving spindle extending downwardly from said table, driving means carried by said spindle, a cup-like centering member surrounding and rotatable with said table and longitudinally movable relatively thereto, and yielding means biasing said cup-like member toward said upper clamp and means for drivingly connecting said spindle with said centering member.

9. In a beverage mixing machine, a container-supporting element comprising a bracket including upper and lower arms, one of which is movable relatively to the other to engage and clamp the container, a downwardly facing container-engaging clamp carried by and rotatable with respect to said upper arm, an axially stationary upwardly facing supporting table carried by and rotatable with respect to said lower arm, a cup-like centering member surrounding and rotatable with said table and movable longitudinally therewith, a lever arm having one end connected to said centering member and yielding means biasing the opposite end of said lever in a direction to move said centering means toward the bottom of the container.

10. In a beverage mixing machine, a container-supporting element comprising a bracket including upper and lower arms, one of which is movable relatively to the other to engage and clamp the container, a downwardly facing container-engaging clamp carried by and rotatable with respect to said upper arm, an upwardly facing axially stationary container-supporting table carried by and rotatable with respect to said lower arm, separable fingers associated and rotatable with said table and movable toward and away from a container supported by said table, and yielding means biasing said fingers into container-engaging movement.

11. In a beverage mixing machine, a container-supporting element comprising a bracket including upper and lower arms, one of which is movable relatively to the other to engage and clamp the container, a downwardly facing container-engaging clamp carried by and rotatable with respect to said upper arm, an upper facing axially stationary supporting table carried by and rotatable with respect to said lower arm, a plurality of container clamping fingers associated and rotatable with said table and longitudinally movable relatively thereto for embracing and centering the bottom of a container and moved into embracing position by the longitudinal movement thereof, and yielding means biasing said arms longitudinally into embracing position.

12. In a beverage mixing machine, a container-supporting element comprising a bracket including upper and lower arms, one of which is movable relatively to the other to engage and clamp the container, a downwardly facing container-engaging clamp carried by and rotatable with respect to said upper arm, an upwardly facing axially stationary container-supporting table carried by and rotatable with respect to said lower arm, clamping arms associated and rotatable with said table, longitudinally movable relative to said table and movable into clamping position by their longitudinal movement, a lever having one end connected to said arms and yielding means biasing the opposite end of said lever in a direction to move said arms into clamping position.

13. In a beverage mixing machine, a base, a rotary table, container supporting elements journaled on said table for tilting and uprighting

movement of the container in a plane substantially radial with respect to said table, said element comprising a bracket including upper and lower arms, one of which is movable relatively to the other to engage and clamp the container, a downwardly facing container-engaging clamp carried by and rotatable with respect to said upper arm, an upwardly facing axially stationary container-supporting member carried by and rotatable with respect to said lower arm, a centering member rotatable with said supporting member, a lever having one end connected to one of said members, yieldable means biasing the opposite end of said lever in a direction to move said supporting member toward said upper clamp, and means for locking said lever in a position to maintain said centering means in its retracted position during a portion of the upright position of said supporting element.

14. In a mixing apparatus, a table, a rotary container-supporting element journaled on said table for tilting and uprighting movement of a container in a plane substantially radial with respect to said table and comprising a bracket including upper and lower arms, one of which is movable relatively to the other to engage and clamp the container, a downwardly facing container-engaging clamp carried by and rotatable with respect to said upper arm, an upwardly facing axially stationary supporting table member carried by and rotatable with respect to said lower arm, a centering member rotatable with said supporting member, movable relatively to the said table, a lever having one end connected to said longitudinally movable centering member, resilient means for biasing the opposite end of said lever to move said member toward said clamp, means for separating said clamping arms during a period of rotation of said rotary table, and means for locking said centering means in its retracted position during said separation.

15. A container-supporting element comprising a bracket including upper and lower arms, one of which is movable relatively to the other to engage and clamp the container, a downwardly facing container-engaging clamp carried by and rotatable with respect to said upper arm, a driving shaft mounted in said lower arm in axial alignment with said container-engaging clamp, a container-supporting table removably mounted on said driving shaft, and an axially movable container centering member removably drivably connected with said shaft and axially movable thereon.

16. A container-supporting element comprising a bracket including a supporting standard, upper and lower arms carried by said standard, one of which is movable relatively to the other to engage and clamp the container, a downwardly facing container-engaging clamp carried by and rotatable with respect to the upper arm, an axially stationary table carried by and rotatable with respect to the lower arms, a container centering member axially movable to engage the bottom portion of the container resting on said table and center the same on said table, a lever pivotally mounted on said standard and having its free arm adapted to engage and move said longitudinally movable centering member, and a spring engaging the opposite end of said lever and biasing said centering member in its raised centering position.

JAMES KANTOR.
